By his attorney,
Nelson Howard

UNITED STATES PATENT OFFICE.

WILLIAM HUBBARD, OF ROCHESTER, NEW YORK, ASSIGNOR TO UNITED SHOE MACHINERY CORPORATION, OF PATERSON, NEW JERSEY, A CORPORATION OF NEW JERSEY.

MACHINE FOR CONCAVING THE BREAST EDGES OF HEELS.

Application filed March 17, 1919. Serial No. 283,138.

To all whom it may concern:

Be it known that I, WILLIAM HUBBARD, a citizen of the United States, residing at Rochester, in the county of Monroe and 5 State of New York, have invented certain Improvements in Machines for Concaving the Breast Edges of Heels, of which the following description, in connection with the accompanying drawings, is a specification, 10 like reference characters on the drawings indicating like parts in the several figures.

This invention relates to cutting machines and is herein illustrated as embodied in a machine for concaving or scalloping the 15 breast-edges of heels.

A machine of this type is shown in the patent to Busell No. 1,030,567 and comprises a frusto-conical milling cutter and a pair of yielding separable gages carrying 20 hooks or stops located adjacent to the cutter. In the operation of such a machine the heel is pushed between the gages into contact with the cutter until its movement is arrested by the stops which engage the breast of the 25 heel a short distance from the tread surface thereof. With the majority of heels the construction, which has been outlined above and is described in detail in the patent, operates satisfactorily, but with certain heels difficulties are experienced. For example, if the 30 heel to be operated upon is a Louis heel and it is desired that the scallop shall extend entirely across the breast-edge of the heel and well up on the breast thereof, the stops if 35 adjusted to produce such a cut, would lie in the path of the cutter. Moreover, even if the desired scallop is of an extent sufficiently smaller than that indicated above so that the stops can be used, the peculiar curve of the 40 breast of a Louis heel does not afford a satisfactory bearing surface with which they may contact.

According to one feature of the present invention improved stop means is provided 45 which extends across the space between the gages in the path of a piece of work which is being moved forward. In the illustrative machine this stop means takes the form of a rod which lies across the breast of the heel 50 well above the tread surface thereof and extends loosely through perforations in the separable side gages so that the separation of the gages is permitted without affecting the

operativeness of the rod. With this construction Louis heels as well as other frequently encountered styles may readily be 55 operated upon.

It is sometimes desired to produce a double scallop, and another feature of the invention relates to a construction whereby this result 60 may be accomplished. In the illustrative machine the side gages may be adjusted so that the distance between them is greater than the width of the heel and then the heel may be presented to the cutter first with one side 65 in contact with one gage and then with the other side in contact with the other gage, whereby there may be formed two scallops which may or may not overlap according to the distance between the gages, the rod referred 70 to above determining the depth of each scallop by limiting the approach of the heel to the cutter.

These and other features of the invention including certain details of construction and 75 combinations of parts will be described as embodied in an illustrative machine and will be pointed out in the appended claims.

Referring now to the accompanying drawings,—

Fig. 1 is a perspective of the operative instrumentalities of a machine in which the present invention is embodied;

Fig. 2 is a plan view, partly in section, and with certain parts omitted, showing a heel 85 in process of being operated upon;

Fig. 3 is a perspective of a Louis heel which has been operated upon, and

Fig. 4 is a more or less conventional view showing how a double scallop may be produced.

The illustrative machine, in its general organization, is similar to the patented machine. The machine frame 2 supports a shaft 4 having a pulley 6 rotated by a belt 8 which may be connected to any suitable source of power. A rotary cutter 10 is secured to the shaft by a screw 12 which permits said cutter to be removed and replaced since cutters of different sizes are 100 commonly used. The cutter is in the form of a frustum of a cone having its largest diameter farthest from the frame of the machine, and its perimeter is made up of a series of blades 14.

Secured to the frame of the machine by

a neck 16 is a cylindrical, horizontally disposed bearing portion 18 upon which a sleeve 26 is slidably mounted. An adjusting screw 22, the stem of which is threaded into the 5 bearing member and rotatable in but held from longitudinal movement with respect to the sleeve 26, furnishes means for adjusting the sleeve and for holding it in adjusted position.

10 Angularly connected with the sleeve 26 is a second sleeve 30, the end remote from the juncture being cut away so as to leave a semi-cylindrical portion. Rotatably mounted in said sleeve but restrained from 15 longitudinal movement with respect thereto is a screw-threaded rod 34 having a milled head 36. This rod is threaded through a screw-threaded portion of a carrier 40 which may be moved longitudinally of the sleeve 20 by rotation of the milled head, this movement being substantially parallel to the cutting edge of the cutter 10—or, more accurately, to that element of the cutter which first contacts with the work. A work-rest 25 42 has an offset portion 44 from which a stem extends downwardly into a pinch-bearing in the carrier 40, a pinch-screw 46 being provided to hold the work-rest in adjusted angular position. In order to position the 30 work-support 42 vertically, a screw-threaded rod 48 is threaded into a boss on the carrier 40 and extends up into engagement with the stem of the work-rest, said rod being provided with a milled head and with a lock-nut 52.

Two rods 54 and 56 are slidably held in the work-rest, and these rods are notched to form racks which engage a pinion 62 placed between them. To the rod 54 is secured an 40 upper side gage 68, and to the rod 56 is secured a lower side gage 74. The lower end of the rod 54 has threaded thereon a thumb nut 76, a spring 78 being located between the upper surface of the nut and the under surface of the work-rest 42. On 45 the upper end of the rod 54 is threaded an adjusting nut 80. With this construction, the gages 68 and 74 are movable equally in opposite directions, the normal distance between them being determined by the position 50 of the adjusting nut 80.

In the operation of the machine, the tread face of the heel of a shoe is placed upon the face of the work-rest 42 and is then presented breast-foremost, to the cutter by being pushed between the separable 55 gages. By manipulating the screw 22, the work rest may be adjusted toward and from the cutter to regulate the depth of the scallop; by manipulating the screw 34, the work-rest may be adjusted parallel to the cutting edge of the cutter to regulate the length of the scallop; and, by loosening the pinch-screw 46 and manipulating the screw 48, the 60 work-rest 42 may be adjusted vertically to

locate the scallop widthwise of the heel. The work-rest may also be adjusted angularly when the pinch-screw 46 has been loosened. The machine, as thus far described, with the exception of the gages 68 and 74, 70 is or may be substantially the same as the patented machine.

In that machine the side gages are provided at their ends nearest to the cutter with stops in the form of hooks which engage the 75 breast of the heel and limit its movement toward the cutter. For certain kinds of heels the patented construction is not suited. In Fig. 3 there is shown a Louis heel having cut therein a scallop of the usual form for 80 such a heel. This scallop, it will be noted, is of a length to extend across substantially the whole width of the heel and is wide enough to extend from five-eighths to three-quarters of an inch up the breast face of the 85 heel. The stops or hooks of the patented machine would obviously contact with the cutter before the work-rest could be adjusted close enough to the cutter to produce this particular scallop. Moreover, even if the 90 scallop were not so extreme, the breast of a Louis heel, owing to its curvature, does not present a satisfactory surface for contacting firmly with the stops of the patented machine. In order then to provide for scallops of the shape shown in Fig. 3 and for other shapes of scallops and heels, the hooks or stops of the patented machine have been removed and replaced by a rod 101 which is freely slidable through perforations formed 95 in blocks 103, said blocks being fast to or integral with the gages 68, 74. In order to prevent the rod from slipping out of the perforations, thumb-nuts 105 are threaded upon its ends. When, now, a heel is placed 100 with its tread face against the supporting surface of the work rest 42 and moved, breast-foremost, toward the cutter, it is arrested by contact of the breast of the heel with the rod, said rod being located at a 105 sufficient distance from the work-rest to permit the formation of a scallop which extends as far up the breast of the heel as is ever desirable. In the patented machine the 110 operative faces of the side gages are flat or substantially so; but in the present machine they are convexly curved to correspond approximately to the concave curvature of the sides of a Louis heel so as to guide the heel accurately in its movement toward the 115 cutter.

It is sometimes desired to produce a so-called double scallop, in which case two comparatively short scallops are made, the adjacent ends of which may be spaced apart, 120 or may meet or the two cuts may overlap, in which case the junction of the two scallops will be rearward of the breast corners. Fig. 4 shows how the present construction may be used to produce this double scallop 130

effect. The figure shows a double scallop in which the two small scallops just meet at their adjacent ends. In producing this and similar effects it may be desirable to use a 5 comparatively small cutter, and in the figure such a cutter is indicated at 110. The adjusting nut 80 is manipulated to separate the side gages 68 and 74 a distance greater than the width of the heel,—in the figure the 10 distance between these gages is approximately one and one-half times the width of the heel. With the gages thus set, the heel is presented first as shown in full lines with one side against one gage, for example the gage 15 68, whereupon the lower scallop is cut and then with its other side against the other gage, whereupon the upper scallop is cut. It should be noted that whatever the 20 position of the gages may be, the stop in the form of the rod 101 always extends across the breast of a heel which is placed between the gages in position to engage the breast of the heel when the desired depth of scallop has been made.

25 Having thus described my invention, what I claim as new and desire to secure by Letters Patent of the United States is:

1. A machine of the class described, having in combination, a tool for operating upon a 30 Louis heel, separable gages adapted to permit the work to be moved forward between them to the tool, and a member shaped to engage firmly the breast of a Louis heel above the tread as it is moved between the 35 gages, located in the path of movement of the heel, and arranged to limit the forward movement of the heel towards the tool.

2. A machine of the class described, having in combination, a tool for operating upon a 40 piece of work, separable gages arranged to permit the work to be moved forward between them to center the work with respect to the tool and a stop-member slidably mounted on the gages to permit their separation and located to engage the work and limit its approach to the tool.

3. A machine for operating on a heel which is attached to a shoe, having in combination, a cutter, a pair of separable gages 50 adapted to permit the heel of the shoe to be moved between them to the cutter without danger of bringing any other part of the shoe into engagement with the cutter, and a member between the gages arranged to extend across the breast of the heel to limit the movement of the work toward the cutter.

4. A machine for producing a scallop in a heel, having in combination, a cutter, a 55 pair of separable gages adapted to permit the heel to be moved between them to the cutter, a rod extending across the space between the gages and located in the path of movement of the work, and slidably

mounted to span the space between the gages 65 in all degrees of separation, and means whereby the relative positions of the rod and the cutter may be varied.

5. A machine for producing a scallop in a heel, having in combination, a cutter, a 70 pair of separable gages adapted to permit the heel to be moved between them to the cutter, a member movable to span the space between the gages in all degrees of separation and located in the path of movement of the work, and means whereby the 75 relative positions of the gages and member and that of the cutter may be varied.

6. A machine for producing a scallop in a heel, having in combination, a cutter, a 80 pair of separable gages for engaging the sides of the heel, and a stop-member mounted partly in one gage and partly in the other and located to extend across the path of the heel to limit the extent of movement 85 of the heel toward the cutter.

7. A machine for producing a scallop in a heel, having in combination, a cutter, a 90 pair of separable gages for engaging the sides of the heel, and a single stop-member mounted slidably in the gages and located to extend across the path of the heel to limit the extent of movement of the heel toward the cutter.

8. A machine for producing a scallop in a heel, having in combination, a cutter, a 95 pair of separable gages for engaging the sides of the heel, and a stop-rod carried by the gages and located to contact with the breast of the heel as the heel is moved toward the cutter.

9. A machine for producing a scallop in a heel, having in combination, a cutter, a 100 pair of separable gages for engaging the sides of the heel, said gages having alined 105 perforations, a stop-rod extending loosely through said perforations, and means for adjusting the gages toward and from each other in a path substantially parallel to the axis of the rod.

10. A machine of the class described, having in combination, a cutter, a pair of gages located at equal distances on opposite sides of the axis of the cutter, and spaced apart a distance greater than the width of the 110 work to be operated upon to guide the work as it is presented successively in engagement with different gages to produce two differently positioned cuts by successive operations of the cutter, and a member extending 115 across the space between the gages in position to limit the approach of the work to the cutter when either gage is being used to guide the presentation of the work.

11. A machine for producing a plurality 120 of scallops in a heel, having in combination, a cutter, a pair of gages adapted to engage respectively the sides of the heel, means for

adjusting the gages to a position in which the distance between them is greater than the width of the heel, and a stop-member connecting the gages and mounted to permit said adjustment whereby the heel may be presented to the cutter first with one side in engagement with one gage and then with

the other side in engagement with the other gage, the depth of the scallop being determined in both presentations by contact of the heel with the stop member.

In testimony whereof I have signed my name to this specification.

WILLIAM HUBBARD.
